UNITED STATES PATENT OFFICE.

EDWIN J. MURPHY, OF RUGBY, ENGLAND, ASSIGNOR TO GENERAL ELECTRIC COMPANY, A CORPORATION OF NEW YORK.

ELECTRIC-ARC LAMP.

No. 823,958.

Specification of Letters Patent.

Patented June 19, 1906.

Application filed September 9, 1904. Serial No. 223,843.

To all whom it may concern:

Be it known that I, EDWIN J. MURPHY, a citizen of the United States, residing at Rugby, in the county of Warwick, England, have 5 invented certain new and useful Improvements in Arc-Lamps, of which the following is a specification.

This invention relates to arc-lamps, and particularly to lamps arranged for the production of light from two or more electric arcs connected in series across constant-potential mains.

The common practice heretofore in the design and construction of lamps having two or 15 more sets of electrodes connected in series for use on constant-potential circuits has been to provide the lamps with means whereby after a definite period of operation the movable electrodes are held against further movement 20 until the arcs increase in length so much that they snap, and thus open the circuit, whereupon the movable electrodes drop into engagement with the stationary electrodes and new arcs are struck. By causing the circuit 25 through the lamps to break in this way before the electrodes are fed the points of the electrodes of each set are separated by approximately equal distances, excessive variations in the consumption of the electrodes of the 30 several sets are largely prevented, and the operating mechanism of the lamp is greatly simplified, since both or all the movable electrodes are acted on as a unit.

My invention relates to an arc-lamp of this 35 type having means for opening the circuit through the lamp before feeding the electrodes. The means which I employ is an electromagnetic stop which arrests the movement of the electrode-positioning mechanism 40 when in a definite relation and holds it against movement until the circuit is broken. This electromagnetic stop preferably consists of a plate of magnetic material bridging the poles of the core of the actuating-solenoids or 45 operating with the armature of the operating magnets in a magnet type of lamp. This plate is held to the core or armature until the movable electrodes have been fed forward a definite amount, when it engages the top of 50 the solenoids or some other member mounted stationarily in the lamp and prevents further feeding of the electrodes until the circuit is broken, when, of course, the solenoids or mag-

nets are deenergized and the plate released from the core or armature.

The novel features of my invention will be pointed out with particularity in the appended claims.

The details of construction and the mode of operation of my improved arc-lamp will be 60 better understood by reference to the following description, taken in connection with the accompanying drawing, which shows diagrammatically the preferred embodiment of my invention.

Referring to the drawing, 1 1 indicate solenoids, and 2 a U-shaped core or armature the legs of which extend within the solenoids. Suspended from core 2 is a bracket 3, to which are secured the vertically-adjustable 70 connecting-rods 4 4, and pivotally connected to these rods are the pawls 5 5, which at their opposite ends are pivoted in ears on the clutch-rings 6 6 for the movable electrodes. In the drawing two sets of electrodes are 75 shown, but it is evident that more may be employed, if desired.

7 indicates a gas-cap in which are insulating-bushings 8 8, through which the movable electrodes 9 9 extend and on which the yokes 80 6 6 impinge to trip the clutches, and thus allow the electrodes 9 9 to drop into engagement with the stationary electrodes 10 10.

Secured to the ends of the legs of the U-shaped armature or core 2 are extensions 11 85 11, of steel, iron, or other material which has magnetic properties, but which preferably is less permeable than the material of core 2, and in the ends of these extensions are the guide-pins 12 12, of brass or other non-magnetic material. Resting on the ends of the extensions 11 11 of the core or armature 2 and arranged to slide readily on the pins 12 12 is a plate or auxiliary armature 13, of iron or other material of good permeability, which 90 constitutes the magnetic stop. A portion of the flux from the coils 1 1 threads the extensions 11 11 and the plate 13, so that the latter is held down upon the ends of the extensions with considerable strength. A dash-pot 19 95 is secured to the pins 12 12 and to a stationary portion of the lamp or in any other suitable relation to dampen the movements of core 2.

Circuit through the lamp is completed 105 from the positive main 14 through a cut-out

switch 15, a resistance 16, and through the solenoids 11 in series to one of the movable electrodes 9. The stationary electrode 10 corresponding thereto is connected to the movable electrode of the other pair, and the stationary electrode of that pair is connected to the negative main 18. The drawing shows the position of the parts just after the arcs have been struck. As the electrodes 10 are consumed the core 2 falls gradually, permitting the movable electrodes to approach the stationary electrodes to maintain a constant length of the arcs. After the lamp has been in operation for an interval the core 2 falls enough to bring the plate 13 into engagement with the tops 17 of the spools of the solenoids 11. The flux passing from the legs of the core 2 through the extensions 11 11 and through the plate 13 holds the core to the plate with sufficient strength to prevent any further drop, and hence the movable electrodes 9 9 are held against further downward movement. The arcs therefore increase in length as the electrodes are consumed, until finally the drop in voltage across the arcs is so great that they are snapped and the circuit broken. The solenoids 11 are thus deenergized, plate 13 is released from the extensions 11 11, and core 2 falls by gravity, so that the yokes 6 6 hit upon the bushings 8 8 or any other suitable tripping-platform and the clutches are tripped. As the core 2 falls the pins 12 12 slide loosely through the openings in plate 13 until the heads of the pins catch upon the plate 13, and thus limit the downward movement. The clutches being tripped permit the movable electrodes 9 9 to fall into engagement with the stationary electrodes 10 10, and as this 40 closes the circuit again the solenoids raise core 2 and the core raises plate 13, so that all parts are again in the position illustrated. It will thus be seen that the circuit is interrupted only momentarily when feeding of the electrodes is necessary, that both arcs are struck simultaneously, so that they are at all times approximately equal in length, and that a single mechanism positions both of the movable electrodes.

50 I have illustrated and described herein an arc-lamp having two or more sets of electrodes therein operated by a single feeding mechanism of the solenoid type; but I do not wish to be understood as limited in this respect. The principles of my invention are also applicable to lamps having magnets to operate the electrode-positioning devices instead of the solenoid type of lamp shown or to lamps in which distinct feeding devices are used for

the several arcs. All such modifications of the construction herein shown I consider within the scope of my invention, and I aim to cover them in the claims appended hereto.

What I claim as new, and desire to secure by Letters Patent of the United States, is—

1. A twin-arc lamp having a plurality of movable electrodes, an electromagnetic winding and a core or armature therefor for positioning the movable electrodes, and a member made of magnetic material adapted to be 60 acted upon magnetically by said winding to arrest the movement of the electrode-positioning mechanism when in a definite position.

2. A twin-arc lamp having a plurality of 75 movable electrodes, a solenoid coil and an armature coöperating therewith for positioning the electrodes, and an auxiliary armature movably mounted in proximity to said armature and adapted to be actuated by the 80 flux of said coil to arrest the movement of said armature when the latter has reached a definite position.

3. An arc-lamp having a movable electrode, two solenoid-coils and a U-shaped core 85 coöperating therewith for positioning the electrode, and an auxiliary armature mounted in proximity to the legs of said core and adapted when attracted to arrest the movement of the core when the latter has reached 90 a definite position.

4. An arc-lamp having a movable electrode, a pair of solenoids and a U-shaped core therefor for positioning the electrode, and an auxiliary armature adapted to bridge 95 the ends of the legs of said U-shaped core and to impinge on the ends of the solenoids.

5. In an arc-lamp, two solenoid-coils, a U-shaped core, the legs of which extend through said coils, guide-pins in the ends of said legs, 100 and a plate of magnetic material loosely mounted on said pins and adapted to bridge the ends of the legs of said core.

6. In an arc-lamp, two solenoid-coils, a U-shaped core, the legs of which extend within 105 the coils, extensions on the ends of said legs of material which is less permeable than that of the core, guide-pins in the ends of said extensions, and a plate of magnetic material loosely mounted on said pins and adapted to 110 bridge the ends of said extensions.

In witness whereof I have hereunto set my hand this 24th day of August, 1904.

EDWIN J. MURPHY. [L. s.]
